UNITED STATES PATENT OFFICE.

ALOYSIUS RITTERBECK, OF WEST HOBOKEN, NEW JERSEY, ASSIGNOR TO PARK & TILFORD, OF NEW YORK, N. Y., A CORPORATION OF NEW YORK.

DESIGN FOR AN OLIVE-OIL BOTTLE.

61,380.

Specification for Design.

Patented Aug. 15, 1922.

Application filed September 26, 1921. Serial No. 503,401. Term of patent 7 years.

To all whom it may concern:

Be it known that I, ALOYSIUS RITTERBECK, a citizen of the United States, and residing at No. 349 West Street, in the city of West Hoboken, county of Hudson, State of New Jersey, have invented a new, original, and ornamental Design for an Olive-Oil Bottle, of which the following is a specification, reference being had to the accompanying drawing, forming a part thereof.

Figure 1 is a side elevation view of my olive oil bottle, and Figure 2 is a top plan view of my said bottle showing my new design.

I claim:

The ornamental design for an olive oil bottle as shown.

ALOYSIUS RITTERBECK.
